UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

COP-CONE.

1,391,961.

Specification of Letters Patent. Patented Sept. 27, 1921.

Application filed September 22, 1920. Serial No. 411,968.

To all whom it may concern:

Be it known that I, JOHN O. McKEAN, a citizen of the United States, and resident of Westfield, in the county of Hampden and State of Massachusetts, have invented a new and useful Improvement in Cop-Cones, of which the following is a specification.

My invention comprises a cop cone having two different tapers as distinguished from 10 the cones in common use which have a single straight taper.

My invention more particularly comprises a cop cone having a gradual taper extending for a distance from its larger end, said 15 gradual taper terminating at the smaller end of the cone in a steeper taper, preferably straight, although it may be slightly convex or slightly concave if so desired.

On a single taper cone as hereinbefore 20 used, the extreme end of the smaller diameter builds up somewhat larger than the true taper. This is one of the disadvantages which it is intended to obviate by the double taper cone of the present invention.

25 Another advantage of the double taper cone is that it gives more clearance to the cop than a single taper cone unless the single taper is very steep. In a very steep taper cone it is impossible to get the yardage 30 in the cop. In the double taper cone a greater mass of yarn with the same clearance of the thread may be wound. The double taper cone seems to have a firmer nose and is not so liable to be injured in the 35 rough usage to which it is subjected, as the nose or smaller end of the cone seems to be protected by the steep taper at the smaller end of the cone. Furthermore, in a very steep taper to allow for the proper clearance, the yarn has a tendency to come off 40 in coils and snarls. This is obviated by the double taper of the cone, the yarn seeming to cling much better and not to uncoil faster than required.

45 A practical embodiment of my invention is represented in the accompanying drawings, in which,

Figure 1 represents my improved double cop cone when made of paper, the cone being shown in its operative relationship to 50 its driving roll.

Fig. 2 represents a similar view showing a wooden double taper cone.

Fig. 3 represents in outline, the cop wound

on the cone, together with the driving roll 55 therefor.

Fig. 4 represents a detail view showing another form of steeper taper at the smaller end of the cone.

Fig. 5 represents a similar view, showing 60 still another form of steeper taper at the smaller end of the cone.

The driving roll which is herein shown, comprises a cylindrical member 1 and a flaring member 2, both mounted on a suitable 65 supporting shaft 3. In the form shown in Fig. 1, the cop cone is represented as a paper cone and it has a gradual taper as shown at 4, extending a distance from its larger end, said gradual taper terminating in a 70 steeper taper shown at 5, at its nose or smaller end.

In the form shown in Fig. 2, the cop cone is of wood or other suitable material. In both of the forms of cop cones illustrated 75 in Figs. 1 and 2, the steeper taper 5 of the cone is straight.

In the form shown in Fig. 4, the steeper taper of the cone is shown as slightly convex, while in the form shown in Fig. 5, the 80 steeper taper of the cone is shown as slightly concave.

It will be understood that in the winding machine, the gradual taper 4 of the cone is opposite the cylindrical member 1 of the 85 driving roll and the steeper taper 5 of the cone is opposite the flaring member 2 of the driving roll. This arrangement of the driving roll and double taper cone permits the winding of the cop so as to produce the 90 advantageous results hereinbefore set forth and eliminates some of the disadvantages which have heretofore obtained where a single taper cone has been employed, especially with the driving roll having the flaring 95 member herein illustrated.

It is evident that various changes may be resorted to in the form, construction and arrangement of the several parts without departing from the spirit and scope of my 100 invention; hence I do not intend to limit myself to the particular embodiments herein shown and described, but,

What I claim is:—

1. A rigid cop cone, its winding surface 105 having a gradual taper terminating at its smaller end in a steeper taper in the same direction.

2. A rigid cop cone, its winding surface having a gradual taper terminating at its smaller end in a straight steeper taper in the same direction.
- 5 3. In a winding machine, the combination with a driving roll divided into a cylindrical member and a flaring member, of a rigid cop cone, its winding surface having a gradual taper opposite the cylindrical member terminating at its smaller end in a steeper taper in the same direction opposite the flaring member.
- 10 4. In a winding machine, the combination with a driving roll divided into a cylindrical member and a flaring member, of a rigid cop cone, its winding surface having a gradual taper opposite the cylindrical member terminating at its smaller end in a straight steeper taper opposite the flaring member.

15
20 In testimony, that I claim the foregoing as my invention, I have signed my name this eighteenth day of September, 1920.

JOHN O. McKEAN.
